UNITED STATES PATENT OFFICE.

WILLIAM H. ELLIS, OF TWO RIVERS, WISCONSIN.

SHEET-METAL HOT-WATER AND SHEET-METAL IRRIGATING BOTTLE.

1,272,238.

Specification of Letters Patent. Patented July 9, 1918.

Application filed January 18, 1918. Serial No. 212,503.

To all whom it may concern:

Be it known that I, WILLIAM H. ELLIS, a citizen of the United States, and resident of Two Rivers, in the county of Manitowoc and State of Wisconsin, have invented certain new and useful Improvements in Sheet-Metal Hot-Water and Sheet-Metal Irrigating Bottles; and I do hereby declare that the following is a full, clear, and exact description thereof.

This invention relates to improvements in sheet metal containers, particularly water bottles.

The principal object of the invention is to provide a device of this character which can be used either as a hot water bottle or as an irrigating bottle.

An additional object is to provide a novel arrangement for forming screw threads on the sheet metal neck of the device for the reception of a screw cap.

A still further object is to provide an improved foldable hanger element for use when the receptacle is to be operated as an irrigating bottle.

With the foregoing and other objects in view, my invention resides in the novel construction, combination and arrangement of parts substantially as hereinafter particularly described and claimed, it being understood that such changes in the precise embodiment of the herein-disclosed invention may be made as come within the scope of the claims.

In the drawing, Figure 1 represents a side elevational view of a bottle constructed in accordance with my invention, parts of the same being broken away and in section, said bottle being provided with the cap which is used when the device is to form a hot water bottle.

Fig. 2 is a sectional view through the upper end of the improved bottle and cap, the latter being equipped with means for connecting an irrigating tube thereto.

Referring more particularly to the drawing wherein similar reference characters denote like parts in both of the views, it will be seen that the numeral 1 indicates a bottle which may be of any convenient or desired shape and size, depending upon the purpose to which it is to be put. This bottle is preferably formed of sheet metal, it being constructed of two identical halves which have their edges welded or otherwise connected together.

The bottle is provided with a reduced cylindrical neck 2 to receive a polygonal headed cap 3 having a cylindrical internally threaded sleeve 4 formed integrally therewith. Inasmuch as it is impossible to properly form or cut screw threads in the sheet metal neck 2, I cast a metallic collar 5 thereon, said collar being of sufficient thickness to permit external screw threads to be cut therein for co-operation with the internal threads on the sleeve 4. To aid in holding the collar in position, the end of the bottle adjacent the connection of the neck thereto is shouldered as at 6, and the free edge of the neck is flared outwardly as at 7.

The head of the cap 3 is provided with a central screw threaded opening 8 to receive either the threaded shank of a closure plug 9 or the similar portion of a nipple 10. When the container is to be used as a hot water bottle the opening 8 is closed by the plug 9 as shown in Fig. 1. But, when it is used as an irrigating bottle the opening 8 receives the nipple 10 on which is disposed an irrigating tube 11 of any appropriate length. A central passage-way 12 through the nipple 10 and the shank thereof provides an outlet from the interior of the bottle to the tube 11.

Also, when the container is to be used as an irrigating bottle a hanger element is brought into play. This element is in the form of an eye 13 pivoted in a fulcrum block 14 secured within a recess 15 formed in the bottom of the bottle. This recess is of sufficient size and depth to house the eye and its block when the former is in folded or inoperative position. When the device forms an irrigating bottle it is obviously inverted and the eye 13 disposed over a hook or the like, said eye being extended into the dotted line position shown in Fig. 1 when so used.

In the recessed portion at the bottom is formed a vent normally closed by a plug 16 adapted for use when the device is operated as an irrigating bottle. It will be noted that the plug does not extend beyond the bottom of the bottle and therefore will not interfere with standing the same on its end.

With a container of this nature together with the necessary attachments, it is obviously unnecessary to provide separate hot water and irrigating bottles as is now customary. By constructing the same largely of sheet metal the cost of manufacture is reduced to a minimum. The novel arrange-

ment for screw threading the neck of the bottle and the improved cap therefore are considered important features of my invention.

5 I claim:-

1. A device of the class described comprising a container adapted to normally stand on its bottom, said bottom having a depression, a vent in said depression, a fulcrum 10 block secured in said depression, and an eye pivoted to said block, said eye being normally disposed in said depression when the container is seated on its bottom, and movable outwardly at right angles to provide a hanger for supporting the container when held in an inverted position.
- 15 2. A combination water and irrigating

bottle adapted to normally seat on its bottom and having an outlet from its top, a closure cap for the opening, said cap being 20 constructed to permit the attachment of a hose connection having communication with the interior of the bottle, the bottom of the bottle having a depression, a hanger element 25 normally disposed within said depression and movable outwardly therefrom to provide a support for the bottle when in an inverted position, and a vent in said depression.

In testimony that I claim the foregoing I have hereunto set my hand at Two Rivers, in 30 the county of Manitowoc, and State of Wisconsin.

WM. H. ELLIS.
